UNITED STATES PATENT OFFICE

96,025

DESIGN FOR A COMBINED WEIGHING AND ADVERTISING DEVICE

Guy G. Eidman, Houston, Tex.

Application September 4, 1934, Serial No. 53,191

Term of patent 14 years

To all whom it may concern:

Be it known that I, Guy G. Eidman, a citizen of the United States and residing at Houston, in the county of Harris and State of Texas, have invented a new, original, and ornamental Design for a Combined Weighing and Advertising Device, of which the following is a specification, reference being made to the accompanying drawing, forming a part thereof.

In the accompanying drawing, Fig. 1 is a front elevation of a combined weighing and advertising device showing my new design; and Fig. 2 is a side elevation thereof.

I claim:

The ornamental design for a combined weighing and advertising device, substantially as shown.

GUY G. EIDMAN.
